UNITED STATES PATENT OFFICE.

JAMES C. BAYLES, OF NEW YORK, N. Y.

PAVEMENT, FLOOR, &c., COMPOSED OF PLASTIC MATERIAL.

SPECIFICATION forming part of Letters Patent No. 781,869, dated February 7, 1905.

Application filed December 14, 1903. Serial No. 185,139.

To all whom it may concern:

Be it known that I, JAMES C. BAYLES, a citizen of the United States, residing in the city of New York, county and State of New York, have invented a new and useful Improvement in Pavements, Floors, &c., Composed of Plastic Material, of which the following is a specification, reference being had to the accompanying drawings, in which—

10 Figure 1 shows in plan view a pavement constructed in accordance with my invention. Fig. 2 is a vertical cross-section thereof. Figs. 3 and 4 show in plan view modified forms of the grille.

15 My invention relates to improvements in road-surfaces, street-pavements, and other surfaces made from material plastic at the time of use, such as asphalt, concrete, or cement.

20 The object of my invention is to correct the defects which are found in practice to exist in pavements and other surfaces of material laid in a plastic condition. In the case of asphalt roadways and street-surfaces these defects are (a) their dangerous slipperiness when 25 wet or cold, causing horses to fall upon them; (b) their inability to afford an adequate foothold for horses when drawing heavy loads, in stopping quickly, or in backing; (c) their tendency to wear unequally; (d) their tendency 30 to flow or creep in hot weather. To correct these features, I employ the device shown in the accompanying drawings, which show grilles for use in connection with a plastic material employed to give a wearing-surface in 35 roadways for vehicles or pedestrians.

In the drawings, 2 are the grilles, and 3 the plastic material, of the pavement.

40 In carrying out my invention as applied to the improvement of roadways, street-surfaces, lanes, &c., laid with asphalt or other bituminous material I prepare my grilles by bending flexible strips or ribbons of iron or steel into the form best adapted to accomplish the objects immediately in view. The strips or ribbons of iron or steel are of such thickness and width as the traffic and other conditions may require. In connection with asphalt street-pavements in ordinary practice I shall make my grilles of strips or ribbons of iron or steel 45 about one inch wide and about one-eighth of

an inch thick, each long enough to form from one piece by bending edge up a grille covering a superficial area about twelve inches square. It will be understood that the width or thickness of the strip or ribbon, the pattern into which it is to be bent or folded, and the superficial area of the grille are not arbitrary, but may be varied as may be found advantageous in dealing with given conditions. One general form or pattern which will be found especially 55 advantageous and useful is that in which the free ends of the strip are so disposed by the bending as to place them within the periphery of the pattern. One of the many patterns which may be thus constructed is shown in 60 Fig. 4, and the obvious advantage of such a pattern is that the free end is thus shielded by the surrounding convolutions of the strip and is prevented from being exposed and turned upward out of a plastic material by any unusual wear or lifting, such as might result from 65 contact with a horseshoe-calk, especially when the plastic material is softened by heat.

70 In laying a new asphalt pavement or relaying an old one by resurfacing it after the superficial layer is spread and partly smoothed I dispose my grilles edgewise in position, hot or cold, as may be found most advantageous, and partly embed them in the plastic material with which they are to be incorporated by 75 malleting or pressure. I then pass a road-roller back and forth over them, condensing the material and at the same time pressing the grilles into the plastic material until the 80 upper edges of the folds or convolutions composing them are flush with the surface. They are thus incorporated into the plastic material of the wearing-surface of the pavement, dividing it by lines of metal so disposed as best to 85 accomplish the purpose sought in each instance. Being harder and more resistant to wear than any bituminous or other plastic material, the grilles do not wear down as fast as the material in which they are inserted, and by the slight protrusion of the edges of the 90 bent strips of metal from which they are formed they give the foothold to horses required and equalize the wear of the street-surface. The grilles do not extend through 95 the wearing-surface to the rigid base of the 100

pavement, but terminate above the same, as shown in Fig. 2, and being of flexible nature the elasticity of the pavement is preserved and all inequality of wear is prevented. It is therefore important that the grilles should not be composed of a rigid frame or structure.

I claim—

1. A pavement formed of plastic material having embedded edgewise in its surface a grille consisting of a single strip of metal folded to bring the edges of the folds into a common plane; substantially as described.
2. A pavement formed of plastic material having embedded edgewise in its surface, and terminating above the rigid base of the pavement, a grille consisting of a metal strip folded to bring the edges of the folds into a common plane; substantially as described.
3. A pavement formed of plastic material

having embedded edgewise in its surface a grille consisting of a strip of metal having its ends bent within the periphery of the pattern formed from said strip; substantially as described.

4. A grille for insertion into plastic pavement, consisting of a single strip of metal having its ends bent within the limits of the figure formed from said strip; substantially as described.

5. A pavement-protecting grille consisting of a single strip of metal bent to form its edges into an approximately rectangular, plane figure; substantially as described.

JAMES C. BAYLES.
